DESIGN FOR A LENS CLIP

Bernard Spero, Chicago, Ill., assignor to Belgard-Spero, Inc., Chicago, Ill., a corporation of Delaware

Application February 1, 1934, Serial No. 50,581

Term of patent 14 years

To all whom it may concern:

Be it known that I, BERNARD SPERO, a citizen of the United States, residing at Chicago, Illinois, in the county of Cook, State of Illinois, have invented a new, original, and ornamental Design for a Lens Clip, of which the following is a specification, reference being had to the accompanying drawing forming a part thereof, in which:

Figure 1 is a perspective view of a lens clip, showing my new design; and Fig. 2, a side view on a smaller scale of the rear side of the clip.

I claim:

The ornamental design for a lens clip, as shown and described.

BERNARD SPERO.
